UNITED STATES PATENT OFFICE.

WILLIAM HENRY CONE, OF BERLIN, ONTARIO, CANADA, ASSIGNOR TO
THE CONE GAS MACHINE CO., OF DETROIT, MICHIGAN, A CORPO-
RATION OF MICHIGAN.

GAS-PRODUCER.

No. 830,884.

Specification of Letters Patent.

Patented Sept. 11, 1906.

Original application filed June 7, 1905, Serial No. 264,173. Divided and this application filed August 31, 1905. Serial No. 278,611.

To all whom it may concern:

Be it known that I, WILLIAM HENRY CONE, of the town of Berlin, in the county of Waterloo, in the Province of Ontario, Canada, have 5 invented certain new and useful Improvements in Gas-Producer Generators, of which the following is the specification.

My invention relates to improvements in gas-producer generators; and the object of 10 the invention is to produce a generator by which the formation of air-channels in the body of the fuel will be prevented, and consequently a gas of a superior quality produced, and second objects are to dispense with the 15 ordinary expansion-chambers used between the generator and point of combustion. To carry out these objects, I have constructed and arranged my generator, as hereinafter more particularly explained.

20 Figure 1 is a sectional perspective view of my generator. Fig. 2 is an enlarged detail of the valve for admitting the air.

In the drawings like letters of reference indicate corresponding parts in each figure. 25 A is the casing of my gas-generator, which is preferably cylindrical in form and is provided for the major portion of its height with a fire-brick lining A', surrounding the fire-bed and peep-holes A², so that the operator 30 may be able to see the condition of the fire-bed.

A³ is a ring forming the bottom for the fire-brick.

35 A⁴ is an internal casing forming the lower portion of the fire-bed—that is, the portion in which the ash falls. The casing A⁴ is provided with an outwardly-extending flange A⁵, which is supported on an annular angle-iron ring A⁶. The flange A⁵ has an upwardly-40 extending portion next the casing and forms an annular space around such casing and beneath the fire-brick.

B represents a series of holes arranged in a circle and communicating with such annular 45 space. The sizes of the openings of the holes B are controlled by a ring C, having a series of holes C', which are designed to register or partly register with the holes B, or the ring may be moved to entirely close the holes B. 50 The means for turning the ring C is a handle C², which is suitably connected to the ring and extends out through a slot in the side of

the casing. These openings are designed for a purpose which hereinafter appears.

D is the stationary bottom of the fire-pot, 55 which is conical in form and provided with a projecting central portion D', which is hollow and extends in the form of a conduit down below the conical bottom and laterally to the casing, as shown at D², having connected thereto a suitable flange-pipe D³, provided with a damper D⁴.

D⁵ is a pipe or conduit leading from the annular space surrounding the ash-bed to the conduit D². 65

E is a conical grate which surmounts the bottom D and is provided with a handle E', by which such grate is shaken. It will be noticed that there is a space between the bottom of the internal casing A⁴ and the bottom edge of the grate to facilitate the discharge of the ashes. 70

The top of the conduit D⁵ is closed by means of a valve F, supported on a central stem F', having an eccentric end F², through 75 which extends the laterally-extending stem F³, operated by a handle F⁴. It will now be seen by means of the handle F⁴ the position of the valve F may be regulated, so as to allow of more or less of a draft through the center 80 of the fire-bed, depending upon the condition of the bed as to incandescence.

By the form of my supporting-bottom for the fire-bed the center of the fire-bed is, I find, kept substantially level instead of sub- 85 siding, as is usual, in other forms of grates or fire-bed bottoms of which I am aware.

The top of the casing has superimposed upon it a water-section G, having a central orifice G' and gas-flues G² of much smaller 90 size. It will be noted that the water-section is supported on flanges G³ above the top of the fire-brick in order to allow of the gas passing upwardly through a maximum number of flues G². 95

H is a water-supply pipe by which the water is supplied to the water section or jacket and by which the height of the water in the section may be indicated.

I is a dome provided with a depending 100 large flange I', which is secured to the water-jacket by suitable bolts, as indicated. The dome is also provided with a depending central flange I² and central opening I³, formed

thereby, such opening being on a line with the opening G'.

M is a pipe leading through the fire-brick from a point near the top of the water-section G and within the same to the annular space surrounding the ash-casing A⁴.

M' is a hood surmounting the pipe M and secured to the water-jacket immediately above the pipe and opening in the water-jacket.

N is a valve, the stem N' of which is controlled by a lever N², which is held in any desired position in the quadrant L³ by a suitable pin, as indicated. The position of the valve N may be therefore varied over the pipe M, as may be desired, depending on the amount of steam and air which it is desired to introduce into the fire-bed by means of the openings B.

O is an upwardly-extending boss secured to the top of the water-section and provided with a series of openings O' and a ring-valve O², having corresponding openings O³, such ring-valve being manipulated by a handle O⁴.

(See detail, Fig. 2.) By means of the valve above described the amount of air introduced into the water-section may be regulated to a nicety, so that the steam arising from the water, together with the air, may pass down through the pipe M and up into the bed of fuel through the openings B.

In case of too much steam, which would have a tendency to deaden the fire, I can regulate the ring-valve C, so as to more or less open or close the openings B. I can, of course, close them altogether and introduce air alone, if desired, through the center of the fire by manipulating the valve F and raising the damper D⁴, or instead I can keep the damper D⁴ closed and introduce the air partially through the opening B by manipulating the ring C by the handle C² and manipulating the valve F and allowing the steam-laden air to pass downwardly through the conduit D⁵ and up through the center of the fire underneath the valve F. In fact, I can manipulate the air from the outside, as well as the steam-laden air, to a nicety, so as to produce the best effects in the proper combustion to produce a gas of a uniform and superior quality. I am also enabled, as hereinbefore described, to keep the bed of the fire level by means of the raised center of the bottom for the fire-bed and by changing the drafts of steam-laden air from center to

side, or vice versa. I am also enabled to produce an equilibrium of heat from center to side and prevent air-channels from forming in the body of the fuel at the side and the deterioration in the quality of the gas produced.

This case is a division of that filed by me June 7, 1905, No. 264,173.

What I claim as my invention is—

1. In a gas-generator, the combination with the casing and fire-brick lining forming a fire-pot or gas-chamber, of a water-section superimposed on the top of the casing and leaving a space between the top of the fire-brick and the bottom of the water-section and having gas-flues passing therethrough, and a central orifice extending therethrough, a suitable source of water-supply, a dome surmounting the water-jacket and having a central orifice registering with the central orifice in the water-jacket, a gas-supply conduit extending therefrom and an adjustable air-supply valve communicating with the interior of the water-jacket and extending up through the dome, a pipe or conduit extending from the interior of the water-jacket down through the fire-brick to and communicating with the bottom of the fire-bed, a valve for closing the top of such pipe and means for manipulating such valve as and for the purpose specified.

2. In a gas-generator, the combination with the casing, and fire-brick lining forming a fire-pot or gas-chamber, of a water-section superimposed on the top of the casing and leaving a space between the top of the fire-brick and the bottom of the water-section and having gas-flues passing therethrough, and a central orifice extending therethrough, a suitable source of water-supply, a dome surmounting the water-jacket and having a central orifice registering with the central orifice in the water-jacket, a gas-supply conduit extending therefrom, an adjustable air-supply valve communicating with the interior of the water-jacket and extending up through the dome, a casing surrounding the bottom of the fire-bed, the annular chamber formed around the same into which the pipe aforesaid extends and the valve-controlled opening extending through the casing into the fire-bed from the annular chamber as and for the purpose specified.

WILLIAM HENRY CONE.
